UNITED STATES PATENT OFFICE.

FRITZ SCHABER, OF STUTTGART, GERMANY.

MANIFOLDING APPARATUS.

Application filed July 12, 1926, Serial No. 121,977, and in Germany December 29, 1923.

In the so called writing through processes or manifolding processes, in which the entries to be made are manifolded or written through on to loose sheets, these have heretofore been laid on a writing plate having pins above it, over which the correspondingly perforated sheets and the manifolding, (carbon) paper are laid and firmly clamped by a bar which can be raised therefrom as 10 and when desired. Other types of writing plates employ clamping springs which press upon the plate.

The present invention relates to a writing plate which is distinguished by its simple 15 and durable construction and which permits of the use of accounting sheets of any kind, even those without holes, without the necessity of employing a spring which readily become fatigued or act unevenly. The essential feature of the invention is that the 20 interchangeable sheets are clamped in position by means of a vertically guided clamping bar by a simple screwing movement by clamping screws, while a second loading bar 25 which acts by its weight holds down the sheets which remain permanently on the writing plate such as the manifolding (carbon) paper for example. The screw threads of the clamping screws may therefore in this apparatus be of so rapid a pitch that even 30 a slight rotation suffices to release or clamp the sheets. The two bars may be conveniently placed by means of holes or perforations over pins on the writing plate and so 35 be guided in a straight line. Furthermore there is provided on the right hand side of the writing plate a guide bar which guides and holds in place a rest or support for the hand and also serves for the laying on of 40 forms. For certain purpose this bar lies only with its raised ends on the plate and leaves a slit free between itself and the writing plate in the middle so that such sheets or leaves can be passed therethrough 45 as are wider than the writing plate or leaves of books which cannot be removed therefrom.

The subject matter of the invention is shown in the accompanying drawing which 50 illustrates some constructional forms thereof.

Figures 1 to 4 show the whole of the manifolding apparatus, Fig. 1 being a plan view and Figs. 2 to 4 being side views.

Figure 5 is a cross section through the 55 weighting bar and clamping bar on a larger scale.

Figure 6 is a longitudinal section through the end of weighted bar shown in Figure 1 on a larger scale. 60

Figure 7 shows the weighting bar for the manifolding sheets likewise in longitudinal section.

Figures 8 and 9 are cross sections through further constructional forms of the clamp- 65 ing device.

The apparatus consists of the usual writing plate *a* of any desired material. On these plates are laid the accounting sheets *b* e. g. account sheets, leaves from a journal, 70 statistical forms or the like together with the manifolding sheets (carbons) laid between them and firmly held with their lines in accurate register by devices which substantially constitute the present invention. 75 Accordingly the sheets are held in place as shown in Figures 1 to 6, and 8 and 9 by a clamping bar *d* which lies loosely on the writing plate and is guided by means of fixed pins over which it is laid by means of 80 holes or openings. As guide pins either special pins *e* may be used (see Figures 1 and 3) or the bolts *p* of the screw nuts *q* may be used by means of which as will be 85 hereinafter described, the clamping bar *d* is clamped down upon the writing plate (see Figure 5). The clamping bar *d* may conveniently be raised from the writing plate *a* parallel therewith by springs *f* so that the accounting and manifolding sheets can be 90 conveniently pushed underneath it when the clamping bar is loosened without having to hold it up by the hand. In order to hold the interchangeable sheets in place with their lines in accurate register without 95 further assistance a stop is provided for the sheets which may consist for example of angle pieces *g* specially arranged behind the clamping bar and adjustable for example transversely, (see Figure 8). In order to 100 avoid separate parts the stops may also be formed by the guide pins *p* or *e* of the

clamping bar (see Figures 1 to 4). The carbon sheet which naturally does not need to be changed at every fresh entry, and the reinsertion of which every time with the interchanged sheets would mean a loss of time which must be avoided, is held in place according to the present invention by means of special parts independently of the clamping bar *d*.

- 10 This holding device for the carbon sheet consists either of pins *h* mounted on the writing plate and over which the carbon sheet is placed by a corresponding perforation or of a weighted bar *k*, which is 15 guided in a straight line on pins *l* on the plate and at the same time has its upward movement so limited by studs *l*¹, that the weighting bar can be raised just so high by 20 means of a handle *m* that the carbon sheet can be pushed underneath the bar. The weighted bar *k* may with advantage be so constructed that its entire under surface does not bear upon the writing plate but only its knife-like edge or edge parts *n* on 25 the right hand side while on the opposite side only a support *n*¹ corresponding to the height of the edges *n* is provided so that the weighted bar shall not grip by bearing one-sidedly on its guide pins (see Figure 5). 30 The clamping edges *n* may be conveniently slightly serrated and the surface with which it contacts upon the writing plate also provided with teeth or roughened, (see Figure 7). In like manner the clamping bar *d* may 35 also be so constructed.
- The holding of the interchangeable sheets *b* in place is effected according to this invention by a screw-like movement and through the medium of the clamping bar already described above. According to the 40 figures there are provided herefor screw bolts *p* of suitably rapid pitch of thread attached to the writing plate *a* or passed up through it from below and which for example pass through the clamping bar *d* on to which is screwed a clamping nut *q* which bears upon the clamping bar from above. Instead of a fixed screw bolt and a nut *q* 45 screwed on to it I may obviously also use a screw with a milled head which is screwed into the writing plate or into a nut fixed thereto. The number and pitch of the threads may be any that is desired and for example I may also use a short catch like a 50 bayonet joint as shown in Figure 9. In this case a pin *t*, projecting on both sides for example is pushed through the bolt *s* and in the nut *u* there are provided one or two slots *v* of a curved shape so that the sheets 55 can be gripped or released by a screw-like movement. To prevent the sheets *b* from becoming soiled e. g. by a nail, the pencil or other hard object being unintentionally drawn over them and also to prevent any 60 rucking up of the top loose sheet when writ-

ing on it an underlay *w* for the hand is provided to hold and guide in a guide bar *x* on the right hand side of the writing plate *a* and parallel with the clamping bar *d*. This underlay *w* for the hand is so wide that it fits with a slight amount of clearance just between the clamping bar *d* and the guide bar *x* and is thus both guided and kept in place. According to the invention there is 70 hollowed out between the writing plate *a* and the guide bar *x* a slot *y* as the guide bar only bears at its raised ends and lies like a bridge over the writing plate, so that sheets can be pushed through this slot which are wider than the space between the clamping 80 bar and the guide bar or the leaves of a book which cannot be removed therefrom.

When it is desired to lay sheets on loosely only without loosening the clamping bar *d* and bring them up against the bar the 85 sheets slide very easily between the clamping bar and the writing plate. According to this invention this disadvantage can be easily overcome by arranging small raised portions at short intervals in front of the 90 clamping bar *d* (see Figure 5) which lift the sheet laid on so that it hits up against the clamping bar but cannot pass under it. These raised portions may conveniently be constituted by small pins *z* which are riveted 95 into the writing plate and the raised heads *z*¹ of which project beyond it.

I claim:—

1. A manifolding device comprising a writing plate; a clamping bar adapted to hold the sheets on the plate; a plurality of pins for guiding and holding said bar; a plurality of pins for a carbon sheet; and a weighted bar guided on said second-named pins for holding the carbon sheet on the 105 plate.

2. A manifolding device comprising a writing plate; a clamping bar adapted to hold the sheets on the plate; a plurality of threaded pins for guiding and holding said 110 bar; a nut for each pin for securing the sheets tightly against the plate; a plurality of pins for a carbon sheet; and a weighted bar guided on said second-named pins for holding the carbon sheet on the plate.

3. A manifolding device comprising a writing plate; a clamping bar adapted to hold the sheets on the plate; a plurality of threaded pins for guiding and holding said 115 bar; a plurality of pins for a carbon sheet; a weighted bar guided on said second-named pins for holding the carbon sheet on the plate; and a plurality of springs for the clamping bar in order to raise and hold the bar in an elevated position from the plate to 120 move the sheets under said plate.

4. A manifolding device comprising a writing plate; a clamping bar adapted to hold the sheets on the plate; a plurality of threaded pins for guiding and holding said 125 plate.

- bar; a plurality of pins for a carbon sheet; a weighted bar guided on said second-named pins for holding the carbon sheet on the plate; a nut for each pin for securing the sheets tightly against the plate; and a plurality of springs for the clamping bar in order to raise and hold the bar in an elevated position from the plate when said nuts are loosened to move the sheets under the plate.
5. A manifolding device comprising a writing plate; a clamping bar adapted to hold the sheets on the plate; a plurality of studded pins; and a weighted bar guided on said pins for holding a carbon sheet on the plate; said weighted bar being limited in its upward movement from the plate by the studded pins.
6. A manifolding device comprising a writing plate; a clamping bar adapted to hold the sheets on the plate; a plurality of studded pins; a weighted bar guided on said pins for holding a carbon sheet on the plate, said weighted bar being limited in its upward movement from the plate by the studded pins; and a handle on said weighted bar for raising it from the plate.
7. A manifolding device comprising a writing plate; a clamping bar adapted to hold the sheets on the plate; a plurality of threaded pins for guiding and holding said bar; a plurality of studded pins; a weighted bar guided on said pins for holding a carbon sheet on the plate, said weighted bar being limited in its upward movement from the plate by the studded pins; and a handle on said weighted bar for raising it from the plate.
8. A manifolding device comprising a writing plate; a clamping bar adapted to hold the sheets on the plate; a plurality of threaded pins for guiding and holding said bar; a plurality of studded pins; a nut for each pin for securing the sheets tightly against the plate; a plurality of springs for the clamping bar in order to raise and hold the bar in an elevated position from the plate to move the sheets under said plate; a weighted bar guided on said pins for holding a carbon sheet on the plate, said weighted bar being limited in its upward movement from the plate by the studded pins; and a handle on said weighted bar for raising it from the plate.
9. A manifolding device comprising a writing plate; a clamping bar adapted to hold the sheets on the plate; a plurality of threaded pins for guiding and holding said bar; a plurality of studded pins; a nut for each pin for securing the sheets tightly against the plate; a plurality of springs for the clamping bar in order to raise and hold the bar in an elevated position from the plate to move the sheets under said plate; a weighted bar guided on said pins for holding a carbon sheet on the plate, said weighted bar being limited in its upward movement from the plate by the studded pins; and a handle on said weighted bar for raising it from the plate.

In testimony whereof I affix my signature.

FRITZ SCHABER.
